GARNET W. COEN, OF SAN FRANCISCO, CALIFORNIA.

OIL-FIRED-FURNACE EXTENSION.

1,129,791.

Specification of Letters Patent. Patented Feb. 23, 1915.

Application filed April 1, 1914. Serial No. 828,785.

To all whom it may concern:

Be it known that I, GARNET W. COEN, a citizen of the United States, residing in the city and county of San Francisco and State of California, have invented new and useful Improvements in Oil-Fired-Furnace Extensions, of which the following is a specification.

This invention relates to oil fired furnace extensions, or as is sometimes called Dutch oven extensions for oil fired furnaces.

The object of the invention is to produce an extension of this nature that will insure an absolutely uniform supply of oxygen to the atomized fuel in such a manner as to produce rapid combustion in the front end of the furnace, with a minimum excess of oxygen, and at the same time prevent heat losses from radiation and reflection through the extension; also to provide means for controlling the air supply and guiding it in such a manner as to compel the oxygen of the air to thoroughly mix with the atomized fuel immediately upon its release from the burner tip, and at a point where sufficient heat is stored up to ignite the mixture.

Another object of the invention is to provide a novel construction which permits two different and distinct supplies of air to be admitted to the furnace, a primary and a secondary supply, each separately controlled and so directed as to compel the air currents to come into contact with the atomized fuel from a direction substantially at right angles to the flow of the latter.

Another object is to provide means for preventing the extension proper from being exposed to the heat rays or radiation of the furnace, thus insuring a comparatively cool extension, and preventing heat losses in this manner.

A further object is to provide a deflecting flange in close proximity to the burner tip; this flange performing two important duties, viz: it first deflects the course of the primary air, causing air currents to eddy against the face of the flange and combine with the fuel immediately upon its release from the burner; secondly, it acts as a heat reservoir radiating sufficient heat to ignite the combined carbon and oxygen in close proximity to the face of the flange.

The invention consists of the parts and the construction and combination of parts as hereinafter more fully described and

claimed, having reference to the accompanying drawings in which—

Figure 1 represents a front elevation of the oil fired furnace extension. Fig. 2 is a sectional side elevation of the extension, showing its application to a furnace of a Scotch marine boiler, said section being taken on line X—X, Fig. 1.

Referring to the drawings, A indicates in general the forward end of a suitable form of furnace, and B the furnace extension as applied. The furnace extension proper consists first, of an exterior, annular casing section 2, which may be suitably secured as at 3 to the furnace front. Concentrically positioned with relation to the outer casing is an interior casing 4, and lining the inner surface of same as at 5 is a suitable form of refractory material. Secured to the front end of the outer casing section as at 6, is a front plate 7 in which is formed a central opening 8, and a plurality of radially disposed openings 9. The openings 9 communicate with an exterior annular air duct 10, while opening 8 communicates with a central air passage 11. Suitably secured on the outer end of the inner casing section is a spider bracket 12, and carried by said bracket is a pipe section 13, on the inner end of which is secured a flange 14. Mounted on the outer end of pipe 13, exterior of the front plate 7 is a primary air damper 15, which is slidably mounted with relation to the central opening 8 for the purpose of controlling the admission of air through same. Slidably mounted exterior of the inner casing section is a secondary air damper 16; this damper consists of an annular T-shaped ring which is connected through rods 17 with handle 18 through which it may be moved in or out upon the inner casing section.

The mouth of the furnace opening is, in this instance, lined with a suitable form of refractory material, as indicated at 19, and a central opening 20 of smaller diameter than the exterior of the inner casing section is formed in the refractory material of the furnace. The inner casing section is so positioned as to leave an annular opening between the end of same and the face of the furnace, and the area of this opening may be varied to suit conditions by sliding the secondary damper in or out with relation to the furnace.

For the purpose of preventing the escape of reflected or radiated heat through the annular, exterior air duct an inclined deflecting flange 21 is provided; this is secured in a suitable position with relation to openings 9 in the front plate.

The furnace extension constructed as here shown may be fitted with any suitable form of burner, indicated at 22. The burner will, under normal conditions, extend through pipe 13, and the nozzle of the burner should, for the purpose of producing the greatest efficiency, register with the front face of flange 14. The purpose of the present construction is to provide a furnace extension which will permit a perfect air control with relation to the fuel discharging from the burner. Under normal draft conditions it is desirable to leave the primary damper partly open, as indicated in Fig. 2; this permits the air to enter through the central opening 8 in the direction of the arrows. The central inwardly passing air current is, however, broken up to a certain extent by striking the rear face of flange 14, this producing more or less of an eddy in front of the flange, which causes the fuel and air to thoroughly mix at this point. Air is also permitted to enter through the radial openings 9 in the direction of the arrows. The air is here deflected outwardly in the direction of arrows *a* against the interior surface of the exterior casing section; it then passes down in the direction of arrows *b* between the secondary damper and the front face of the furnace. The air thus admitted to the flame area of the furnace, practically speaking, in front of the nozzle of the burner enters at right angles from all directions and is forced into contact with the atomized oil, thus further assisting to produce a perfect mixture of the fuel and oxygen. The volume of air entering at right angles from the exterior, annular air duct may be easily regulated in volume and velocity by changing the position of the secondary damper. The air admitted through the center opening may similarly be controlled by sliding the primary damper in and out on pipe 12 with relation to the central opening, handles 23 being provided for this purpose. The annular deflecting plate, indicated at 21, not only prevents any reflected heat from escaping through the furnace extension, but also directs the air up into contact with the exterior casing. This keeps the exterior casing and front plate cool and prevents loss of heat in this direction. Flange 14 not only serves the purpose of a deflector for the primary air current, but also acts as a heat reservoir. It has been found during actual practice that the flange becomes intensely hot. This not only heats the air which passes around same, but also raises the temperature of the oil to the flashing point.

The materials and finish of the several parts of the extension are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

1. In a device of the character described, the combination of an exterior casing, an interior casing connected therewith, said casings forming a central primary air passage and an exterior, annular secondary air passage, a pipe supported centrally within the interior casing, a flange on the inner end of said pipe, a damper slidable on said pipe with relation to the primary air passage, and means for regulating the flow of air through the secondary passage.

2. In a device of the character described, the combination of an exterior casing, an interior casing connected therewith, said casings forming a central primary air passage and an exterior, annular secondary air passage, a pipe supported centrally within the interior casing, a flange on the inner end of said pipe, a damper slidable on said pipe with relation to the primary air passage, and a ring slidably mounted exterior of the inner casing to control the flow of air through the secondary passage.

3. The combination with a furnace, of an exterior casing secured thereto, an interior casing secured within the exterior casing, and spaced with relation thereto and the front of the furnace, means for admitting air to the furnace through the interior casing and the exterior thereof, means for regulating the flow of air through the interior casing, and a damper ring slidable on the interior casing, said damper being adapted to regulate the space between the end of the interior casing and the furnace face.

4. A furnace extension, comprising in combination, an exterior casing, an interior casing, said casing forming a central primary air passage and an exterior, annular, secondary passage, a front plate secured to the outer end of said casing sections, said plate having a central opening formed therein which communicates with the primary air passage and a plurality of radially disposed openings which communicate with the secondary air passage, an annular deflecting flange secured to the interior casing, an annular damper ring slidably mounted on the interior casing, and means for regulating the flow of air through the primary passage.

5. A furnace extension, comprising in combination, an exterior casing, an interior cas-

ing, said casings forming a central primary air passage and an exterior, annular, secondary passage, a front plate secured to the outer end of said casing sections, said plate 5 having a central opening formed therein which communicates with the primary air passage and a plurality of radially disposed openings which communicate with the secondary air passage, an annular deflecting 10 flange surrounding the interior casing, a pipe supported centrally within the interior casing, a flange on the inner end of said pipe, and means for regulating the flow of air through the primary passage.

15 6. A furnace extension, comprising in combination, an exterior casing, an interior casing, said casings forming a central primary air passage and an exterior, annular, secondary passage, a front plate secured to the

outer end of said casing sections, said plate 20 having a central opening formed therein which communicates with the primary air passage and a plurality of radially disposed openings which communicate with the secondary air passage, an annular deflecting 25 flange secured to the interior casing, a pipe supported centrally within the interior casing, a flange on the inner end of said pipe, and a damper plate slidable on said pipe with relation to the opening in the primary 30 air passage.

In testimony whereof I have hereunto set my hand in the presence of two subscribing witnesses.
